US0D1035006S

(12) **United States Design Patent** (10) **Patent No.:** **US D1,035,006 S**
(45) **Date of Patent:** **** Jul. 9, 2024**

(54) **DENTAL ALIGNER STORAGE CASE**

(71) Applicant: **Align Technology, Inc.**, San Jose, CA (US)

(72) Inventors: **Ankit Shukla**, San Jose, CA (US); **Fred Ting**, San Jose, CA (US); **Ken Wu**, San Jose, CA (US); **Eric Yau**, Santa Clara, CA (US)

(73) Assignee: **Align Technology, Inc.**, San Jose, CA (US)

(**) Term: **15 Years**

(21) Appl. No.: **29/853,032**

(22) Filed: **Sep. 12, 2022**

(51) **LOC (14) Cl. 24-02**

(52) **U.S. Cl.**

USPC **D24/176; D3/203.1**

(58) **Field of Classification Search**

USPC D24/176, 177, 227, 229; D3/201, 203.1, D3/203.3, 203.6, 203.7, 212, 270, 273; D9/414, 421, 428; D28/82

CPC A61C 7/08; A61C 7/002; A61C 19/02

Primary Examiner — Wan Laymon

(74) *Attorney, Agent, or Firm* — Shay Glenn LLP

(57) **CLAIM**

The ornamental design for a dental aligner storage case, as shown and described.

DESCRIPTION

FIG. 1 is front elevation view of a dental aligner storage case in accordance with the present invention;

FIG. 2 is a back elevation view thereof;

FIG. 3 is a top plan view thereof;

FIG. 4 is a bottom plan view thereof;

FIG. 5 is a left side elevation view thereof;

FIG. 6 is a right side elevation view thereof;

FIG. 7 is a front perspective view thereof;

FIG. 8 is a front left perspective view thereof;

FIG. 9 is another front left perspective view thereof, showing an alternative position of the front cover.

FIG. 10 is a front elevation view of a second embodiment of a dental aligner storage case in accordance with the present invention;

FIG. 11 is a back elevation view thereof;

FIG. 12 is a top plan view thereof;

FIG. 13 is a bottom plan view thereof;

FIG. 14 is a left side elevation view thereof;

FIG. 15 is a right side elevation view thereof;

FIG. 16 is a front left perspective view thereof; and,

FIG. 17 is a front perspective view thereof.
